UNITED STATES PATENT OFFICE.

CHARLES T. BURLIN, OF WHITINSVILLE, MASSACHUSETTS, ASSIGNOR OF ONE-HALF
TO WILSON L. GOODRICH, OF SPRINGFIELD, MASSACHUSETTS.

REPAIRING DEVICE FOR STEAM-HAMMERS.

1,252,084.

Specification of Letters Patent. Patented Jan. 1, 1918.

Application filed March 30, 1917. Serial No. 158,763.

To all whom it may concern:

Be it known that I, CHARLES T. BURLIN, a citizen of the United States, residing at Whitinsville, in the county of Worcester and 5 State of Massachusetts, have invented a new and useful Repairing Device for Steam-Hammers, of which the following is a specification.

This invention relates to a device for use 10 in removing the end of a broken piston rod from a steam hammer and to the method.

The principal objects of the invention are to provide means whereby this rod can be quickly and absolutely removed no matter 15 how hard it sticks; and to provide a construction for that purpose which will involve few parts and can be put in place readily without material loss of time; and also to provide one which will fit hammers 20 of different sizes. Further objects and advantages of the invention will appear hereinafter.

Reference is to be had to the accompanying drawings, in which—

25 Fig. 1 is an end elevation of a steam hammer showing the piston rod broken in the usual manner;

Fig. 2 is a similar view of the hammer showing a preferred embodiment of this invention applied thereto, the hammer being 30 raised;

Fig. 3 is a sectional view on the line 3—3 of Fig. 2, showing an additional feature of the invention;

35 Fig. 4 is a similar section of the same with the hammer down and the parts all ready to commence the loosening operation, and

Fig. 5 is a plan showing the piston rod in 40 section.

This invention is intended to be used in connection with steam hammers which weigh anywhere from a few hundred pounds up to four or five tons. The piston rods which 45 operate these hammers frequently become broken, and so far as I am aware they always break near the top of the hammer so that there is no material amount of rod projecting from the hammer and no convenient

50 way of getting them out. It is customary to jack up the hammer, take out the die, place a pin in a hole that runs up through the hammer, and then lower the hammer on this pin for the purpose of causing the 55 weight of the hammer to force the piston

end out at the top. Although the object is not always accomplished, yet it is a time consuming operation and puts the hammer out of business for several hours and sometimes longer because the hammer sometimes 60 has to be taken out and the pin bored out in another machine. This invention is designed to avoid all this delay and the hard work required in jacking up the hammer in this manner, and is designed especially to take 65 advantage of the steam cylinder for raising the hammer.

The invention is shown as applied to an ordinary form of steam hammer comprising the hammer 10, steam cylinder 11 and piston rod 12. The hammer, of course, is provided with the usual die 13 held in by a key 14 and is also provided with a perforation 15 extending upwardly therethrough in which the end of the piston rod is driven to hold 70 and operate the hammer therefrom. In the drawings the end of the piston rod is shown broken off in a position where it usually breaks.

When the piston rod breaks the weight of 80 the hammer is relieved from it obviously and the cylinder acts to draw the piston rod up to its highest limit, and then a safety device, which is ordinarily used in this type of hammer but is not shown herein, acts to push 85 the piston down nearly into contact with the top of the hammer. These features are old and ordinarily employed. When this accident happens the parts are left in that position and then the first thing necessary in 90 order to perform the necessary repairs is to operate the piston to move it upwardly out of contact with the hammer.

According to the present invention the 95 operation is decidedly changed. The key 14 is removed as usual and the die 13 thus left loose so that it can drop out when the hammer is raised and remain on the block if desired. After the piston is raised I introduce between the piston and top of the cylinder a yoke 20. This is provided with a perforation 21 therethrough which I prefer to make about six inches in diameter so as to receive piston rods of all sizes. It is provided with two legs 22 on each side spaced 100 apart and arranged in horizontal position. This yoke is placed on the top of the hammer and two eye-bolts 23 are applied to its ends in the slots between the legs and secured in proper position by nuts 24 with 110

which they are provided. These are adjusted to the proper place so that the eye-bolts come close to the sides of the hammer and so that the eyes thereof come in alignment with a pair of holes 25 in the sides of the hammer. These holes may extend clear across so as to form a continuous passage if desired. Then pins 26 are introduced through the eyes of the eye-bolts into these holes to hold the parts in position and support the yoke 20 considerably above the top of the hammer so that there is a space thereunder.

10 The piston rod is now brought down through the hole 21 and a collar 27 fastened to it on the underside of the yoke. This can be secured by set screw or the like. Then a plate 28 is laid on top of the hammer under the piston rod and the steam is admitted 15 into the cylinder to draw the device up.

20 The key 14 having been removed the die 13 will be left on the block when the hammer ascends. This can be removed and a plain piece of iron 40 put in its place or it 25 can be used as a base for supporting a driving plug 29 which constitutes part of the repair device. This is placed in alignment with the hole, and on top of it is placed another loosening plug 30 of the same diameter as the plug 29, namely that of the smallest piston rod in use in this class of hammers. The plug 30 is selected of such height as to make the combined lengths of the 30 plugs 29 and 30 almost equal to the height of the hammer. I prefer to have two of these plugs instead of making them all in one, because the lower one 29 can be furnished by the manufacturer of the device suitable for all hammers or preferably of such 35 size and length as to serve for the smallest one and then the user can furnish a set of plugs 30, one for each size of hammer that he has. The plug 29 is provided with a frame 31 connected by chains 32 with 40 springs 33 and a pair of hooks 34. These 45 are laid out on the block at the present time.

50 The next operation consists in operating the cylinder so as to allow the hammer to come down so that the plugs 29 and 30 are brought up into it in the passage therein. This operation is performed gently to place the parts in position. Then the hooks 34 are placed over the pins 26 which project from the screw-eyes sufficiently to hold these 55 parts in position. The parts are now in the position shown in Fig. 4.

Now the piston is raised and then lowered with sufficient force to give a hard blow to the projecting end of the plug 29 which 60 drives the plug 30 up against the end of the piston rod which is stuck in the hammer and force it out against the plate 28 lying on top of it. It is forced out by the pressure of the hammer but it will yield as the 65 force driving it out consists of the force of

the steam cylinder plus the weight of the hammer head. It will be understood of course that the loosening of the end of the piston rod is all that is necessary because it can readily be taken out after it has once 70 been loosened.

In describing the construction I have also described the operation in full. In this way the customary operation consuming hours and sometimes days is reduced to one involving only a few minutes, thus saving more than its cost every time it is used.

It will be understood, of course, that this arrangement can be modified in many ways without departing from the scope of the invention as expressed in the claims and therefore I do not wish to be limited to all the details of construction shown, but what I do claim is:—

1. In a device of the character described, 85 the combination of means for temporarily connecting the end of a broken piston rod with a hammer head to permit the head to be lifted by the broken rod, and means adapted to project up through the hammer head for loosening the broken end therefrom.

2. In a device of the character described, 95 the combination of means for temporarily connecting the end of a broken piston rod with a hammer head, means adapted to project up through the hammer head for loosening the broken end therefrom, and means for connecting the last named means with the first named means while on the hammer. 100

3. In a device of the character described, 105 the combination of a yoke having an opening therethrough adapted to receive the end of a broken piston rod, means adapted to be attached to the end of the piston rod under the yoke to prevent the piston rod being pulled up through the yoke and means for connecting the yoke with the hammer head at a distance above it to furnish a space between them.

4. In a device of the character described, 115 the combination of a yoke having an opening therethrough adapted to receive the end of a piston rod, means for securing the end of the piston rod under the yoke so that the piston rod can be used to lift the same, means for connecting the yoke with the hammer head whereby they will move together, said means being arranged to hold the yoke at a distance above the hammer head and furnish a space between them, and a plate located on top of the hammer head under the end of the piston rod.

5. In a device of the character described, 125 the combination of a yoke having an opening therethrough adapted to receive the end of a piston rod, means for securing the end of the piston rod under the yoke so that the piston rod can be used to lift the same, a pair of screw eyes for connecting the yoke 130

with the hammer head whereby they will move together, said screw eyes being long enough to hold the yoke at a distance above the hammer head and furnish a space between them, means for adjustably connecting said screw eyes with the yoke, and pins for connecting the screw-eyes with the hammer head.

6. In a device of the character described, the combination of a yoke having a passage for receiving the end of a piston rod, said yoke having two pairs of legs extending in opposite directions and having spaces between them, a pair of screw-eyes adapted to be received in said spaces, means for securing said screw-eyes at any desired distance from the center of the yoke and at any desired elevation with respect thereto, and means for securing the screw-eyes to the hammer head.

7. In a device of the character described, the combination of a yoke having a passage for receiving the end of a piston rod, said yoke having two pairs of legs extending in opposite directions and having spaces between them, a pair of screw-eyes adapted to be received in said spaces, means for securing said screw-eyes at any desired distance from the center of the yoke and at any desired elevation with respect thereto, pins adapted to pass through said screw-eyes for securing them to the hammer head, said pins projecting outwardly beyond the screw-eyes, a loosening plug adapted to be inserted in the bottom of the hammer head, and means connected therewith for engaging said pins in the screw-eyes and holding the loosening plug in position.

8. In a device of the character described, the combination of a yoke for temporarily

connecting the end of a broken piston rod with a hammer head, means adapted to project up through the hammer head for disengaging the broken end therefrom, a pair of pins for connecting said yoke with the hammer head, said pins projecting from opposite sides thereof, a loosening plug adapted to enter the bottom of the hammer, two flexible connections connected therewith, and hooks on their ends for engaging said pins to hold the loosening plug temporarily in position.

9. In a device of the character described, the combination of a yoke for temporarily connecting the end of a broken piston rod with a hammer head, a loosening plug adapted to enter the bottom of the hammer, two flexible connections connected therewith, and hooks on their ends for engaging said hammer to hold the loosening plug temporarily in position.

10. The method of loosening the end of a piston rod from a hammer which consists in moving the piston rod down near the top of the hammer, connecting it loosely with the hammer so that it will raise it when elevated, raising the piston rod with the hammer, placing a loosening plug below the hammer, centrally alined therewith, lowering the piston rod and hammer over said loosening plug to insert the plug in the hammer, connecting the loosening plug temporarily with the hammer so that it will necessarily move therewith, and then raising the hammer by means of the piston rod and forcing it down to bring the projecting end of the plug into contact with a stationary surface.

In testimony whereof I have hereunto affixed my signature.

CHARLES T. BURLIN.
